UNITED STATES PATENT OFFICE.

CHARLES IRVING PARKER, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

PARTITION-SUPPORT.

No. 866,881.

Specification of Letters Patent.

Patented Sept. 24, 1907.

Application filed March 20, 1907. Serial No. 363,398.

To all whom it may concern:

Be it known that I, CHARLES IRVING PARKER, a citizen of the United States, residing at New Britain, county of Hartford, Connecticut, have invented certain new and useful Improvements in Partition-Supports, of which the following is a full, clear, and exact description.

My invention relates to improvements in partition supports, the object being to provide an adjustable support whereby any unevenness in the floor may be compensated for in the support proper without the use of wedges and the like.

In the drawings, Figure 1 is a side elevation of a partition support partly broken away in the center. Fig. 2 is a similar view, the upper part being broken away and showing the lower part in section. Fig. 3 is a side elevation of a detail. Fig. 4 is a view of the under side of the supporting device. Fig. 5 is a plan view of the detail shown in Fig. 3. Fig. 6 is a view of a slight modification partly in section.

1 is the usual tubular post or support having at its upper end the saddle 2 of suitable form to receive the partition proper. In partitions of this type there is a space between the lower part of the partition proper 25 and the floor, and in setting up such partitions it is necessary, owing to the fact that floors, particularly cement floors, are slightly uneven, to take up such unevenness by means of wedges or shimming devices. Such a method provides only a make-shift device.

30 By my invention the partition support proper may be adjusted to a nicety, so as to compensate for these variations found in the floor, or, in fact, in the partition itself.

3 is a base arranged to rest upon the floor 4 and to furnish the support for the post 1. This base 3 is of socket form, the post 1 projecting into said socket so as to receive sufficient support from the side as well as from below.

5 is a movable base screw-threaded within the socket 40 3 and supporting directly the end of post 1. This support 5 may be raised and lowered by turning the same in the socket, so that the desired adjustment may be secured. To prevent lateral displacement, the lower end of the support 5 may be extended down-

wardly, as at 5^a, to project into the floor, as shown in Figs. 1, 2 and 6. A screw-driver slit or slits may be provided in this adjustable support whereby the workman may readily adjust the same accurately to the desired height.

In Fig. 6 I have shown a construction in which the lower end of the post 1^a has a rib-like extension 1^b arranged to take into the support 5^b, so that by turning the post 1^a the adjustment may be effected without the employment of a screw-driver or other tool.

Any suitable means may be provided for anchoring the base socket 3 in place against lateral movement, but in the preferred form this is accomplished by means of the extension 5^a. It should be understood that I have shown only the preferred form of the invention, and that the same may be modified in various ways.

What I claim is:

1. In a partition support, the combination of a post, a flanged base adapted to receive the post, an adjustable support for said post within said base, means on said post engaging said support to adjust the same, and means carried by the support to prevent lateral movement of the base.

2. In a partition support, a post, a flanged base engaging the floor provided with a socket to receive said post, an adjustable support within said socket engaging the end of the post and adapted to adjust the same in relation to the floor, and means carried by the support to prevent the longitudinal movement of said base.

3. In a partition support, a post, a flanged base engaging the floor provided with a socket to receive said post, a screw-threaded adjustable support engaging a corresponding screw-threaded portion in said socket adapted to change the relation of the post to the floor, means carried by the post to adjust said support, and means carried by said support to prevent longitudinal movement of said base.

4. In a partition support, a post, a flanged base engaging the floor provided with a socket to receive and support the said post, an adjustable support within said socket, means carried by said post engaging said support to adjust said post by rotation of said base, and means carried by the support to prevent the longitudinal movement of the base.

CHAS. IRVING PARKER.
